ELECTRONIC CLINICAL THERMOMETER

Douglas M. Bauer, Danvers, and Mark S. Mazzetti, Marblehead, Mass., assignors to Meditech Energy and Environmental Corporation, Danvers, Mass.

Filed Nov. 9, 1970, Ser. No. 25,885

Term of patent 14 years

Int. Cl. D10—03

U.S. Cl. D52—7

FIG. 1

FIG. 2

FIG. 3

FIG. 4

FIG. 1 is a perspective view of the electronic clinical thermometer showing our new design;

FIG. 2 is a top plan view thereof;

FIG. 3 is a right side elevational view thereof; and

FIG. 4 is a top plan view of FIG. 2.

We claim:

The ornamental design of an electronic clinical thermometer, substantially as shown.
